UNITED STATES PATENT OFFICE

ALBERT RIVARD, OF OTTAWA, ONTARIO, CANADA, ASSIGNOR OF THIRTY-SEVEN AND ONE-HALF PER CENT TO GASTON RIVARD AND TWENTY-FIVE PER CENT TO ROMAIN LANTHIER, BOTH OF OTTAWA, CANADA

ICELESS REFRIGERATOR

Application filed September 20, 1927. Serial No. 220,760.

This present invention relates to improvements in an iceless refrigerator and appertains particularly to one adapted for domestic use and employing chemical agents as refrigerants.

An object is to provide a refrigerator that is complete in itself and dependent for operation on no extraneous connections.

A further object is to provide a refrigerator that can be cheaply manufactured and whose maintenance is reasonable.

A still further object is the provision of a device of this nature characterized by structural simplicity, durability and efficiency and thereby rendered commercially desirable.

To the accomplishment of these and related objects, as shall become apparent as the description proceeds, my invention resides in the construction, combination and arrangement of parts as shall be hereinafter more fully described, illustrated in the accompanying drawings and pointed out in the claims hereunto appended.

The invention will be best understood and can be more clearly described when reference is had to the drawings forming a part of this disclosure, wherein like characters indicate like parts throughout the several views.

30 In the drawings:—

Figure 1 is a perspective elevation of my improved refrigerator with the doors and top and one of the side curtains removed therefrom;

35 Figure 2 is a vertical section thereof;

Figure 3 is a horizontal section as taken on the line 3—3 of Figure 2; and

Figure 4 is a detail section of one of the container cover closures.

40 The refrigerator is here shown as assuming the outward form of the conventional ice box having a container body 6 supported off the ground by the corner post legs 7. The side walls 8 and back 9 of the body 6, as well as that part of the front of the body not occupied by the doors 10, are unique in that they are formed of multiple layers of material; from the outside in there is first a double layer of wood 11 and 12 spaced from 45 each other by a packing of caulking 13, then

a sheeting of tin, galvanized iron or enamel ware 14, an air space 15 and an inner lining of sheet metal material 16. The top 17 and bottom 18 of the body or cabinet are similarly formed, the former being hinged to 55 permit of opening for a purpose to be later explained. The body being thus designed, it will admit of the penetration of very little heat nor the escape of much cold.

In the air spaces 15 in both sides and 60 across the back of the cabinet I suspend canvas curtains 20 hanging on rods 21 supported at both ends by the hooks 22 suitably located. Weights 23 to hold the curtains open are provided at the bottom thereof.

65 Three shallow flat covered trays 24 superimpose one another providing the interior top and bottom of the refrigerator and the central dividing partition. These trays or containers 24 slope toward the back centre 70 and have small pockets 25 at their bases from which the drain pipes 26 extend that continue downwardly from the base 25 of the top container 24 to the central container, 75 from the base thereof to the lowermost container and from the bottom thereof to empty into a removably drip pan 27 immediately above which the pipe 26 is terminally provided with a trap 28. Immediately below the top two containers 24 an easily accessible 80 stop-cock 29 is tapped in the drain pipe 26 that is positioned centrally close up against the back of the body 6.

85 Each container 24 has a perforated hinged false cover 30 with a second cover 31 immediately underlying that hinged in a supporting cradle housing 32 perforated around its depending edges. Low sunk hinges 33 and a pocketed handle 34 in the top of the surface covers 30 enable the lower two containers to be used as supporting shelves in the refrigerator unimpaired in their usefulness by the presence of the covers.

90 The top 17 and the front door closures 10 are constructed similar to the sides of the cabinet with a double layer of wood with 95 caulking therebetween, a tin sheeting, an air space and an interior finishing of tin with the peripheral edges provided with three steps as at 35 to match and close tightly on 100

sides of the openings to effectively seal the same. When the top 17 is open access is afforded to the air spaces 15 in the sides and back to allow of the removal of the curtains 20 so that they may be soaked in water at convenient intervals. Communication between the air spaces or pockets 15 in which the saturated curtains are pendent and the refrigerator cabinet interior is through a multiplicity of small perforations 36 in the sides or back while like opening 37 through the inner wall 16 into the bottom container 24 provides for drainage from this curtain housing encircling air space or pocket.

15 The several containers 24 are each filled with a mixture 38 of sodium nitrate (NaNO_3) commonly called Chilean saltpetre, fine gravel and water; the solids being always prevented from running out the drain pipes 26 20 by fine wire screens 39 in the pipe openings while the water or saturated solution can be tapped off whenever desired. This mixture is the refrigerant for as the salt dissolves, the solution lowers in temperature and the 25 air in the cabinet compartments becomes chilled, having contact with the solution in the containers through the perforations in the false covers 30 and cradle housing 32 though this construction of covers prevents 30 foreign matter falling into the solution.

This cooling of the air adjacent the containers sets up a circulation or draught that appears to rise in the space where the curtains hang in the walls, entering by the openings 35 near the bottom of the compartments and returning through the openings near the top. This circulation causes some evaporation of moisture from the curtains and this tends to cool the rising current of air even before it enters the compartments at the top. and the loss of moisture is easily replenished by removal of the canvas curtains that are 40 immersed in water and replaced through the open top. The moist gravel whose purpose is 45 to hold the sodium salt open and exposed to the moisture, aids in maintaining an even temperature.

Wire screen trays 40 are adjustably supported on angle brackets 41 and as is quite 50 obvious the number and arrangement of doors may vary and a tell-tale thermometer be provided.

As the construction of the device has thus been described in detail, brief reference is now 55 had to its use and mode of operation: This iceless refrigerator which is of simple construction may be employed for various surfaces to which such a device is adapted and it is apparent that when the containers 24 are 60 filled with the mixture of sodium nitrate (NaNO_3) commonly called Chilean saltpetre, fine gravel and water, the containers will be kept cool and thus cause a lowering 65 of temperature within the refrigerator casing. The curtains 20 may be soaked in water

at continued intervals to keep the same moist and as the air circulating through the air spaces 15 within which the curtains 20 are suspended and into the interior of the refrigerator body above and below the central container 70 75 24, it is chilled and thus lowered in temperature to preserve food and the like resting on the wire screen trays 40, through which the chilled air also may circulate freely. The central and lower containers 24 may also have their upper faces employed as shelves 80 85 upon which to rest articles to be kept in the refrigerator.

With the necessary alterations this system of refrigeration may be successfully employed in connection with meat packing establishments, stores, hotels and the like so that I do not expect to confine myself to the precise embodiment of the invention hereinbefore set forth.

85 From the foregoing description taken in connection with the accompanying drawings, it will be manifest that an iceless refrigerator is provided that will fulfil all the necessary requirements of such a device, but as 90 many changes could be made in the above description and many apparently widely different embodiments of my invention constructed within the scope of the appended claims without departing from the spirit or 95 scope thereof, it is intended that all matters contained in the said accompanying specification and drawings shall be interpreted as 100 illustrative and not in a limited sense.

Having thus described my invention, what 100 I claim as new and desire to secure by Letters Patent is:—

1. A refrigerator comprising a cabinet with heat insulating walls, spaced covered trays superimposing one another, drain pipes 105 connecting said trays, a mixture of sodium nitrate (NaNO_3) and gravel in said trays, moisture diffusing means provided in said cabinet and means for permitting ingress of 110 said moisture to the interior of said trays. 110

2. A refrigerator comprising a cabinet with heat insulating walls, spaced covered trays superimposing one another, perforated hinge covers in the tops thereof, drain pipes connecting said trays, a mixture of sodium nitrate (NaNO_3) and gravel in said trays 115 and wet curtains hung about said cabinet so that the moisture therefrom may be deposited on said sodium nitrate.

3. A refrigerator comprising a cabinet 120 with heat insulating walls, spaced covered trays superimposing one another, drain pipes connecting said trays, fine wire screens protecting the entrances to said drain pipes, stop-cocks in said drain pipes, a mixture of 125 Chile saltpetre (NaNO_3) and fine gravel in said covered trays, and means for moistening said mixture to cause the chilling thereof.

4. A refrigerator comprising a chamber, a 130 tray supported therein adapted to contain a

chemical refrigerant, a ventilated top hinged thereon, a stop-cock controlled drain pipe from said tray and a screen in the upper end of said pipe.

5. A refrigerator comprising a cabinet with heat insulating sides, spaced covered trays superimposing one another, drain pipes connecting said trays, a mixture of salt and gravel in said trays, moisture diffusing means 10 provided in said cabinet and means for permitting ingress of said moisture to the interior of said trays, and circulation of air in said cabinet.

6. A refrigerator comprising a cabinet 15 with heat insulating sides, spaced covered trays superimposing one another, perforated hinge covers in the tops thereof, drain pipes connecting said trays, a refrigerant mixture of salt and gravel in said trays and wet curtains hung about said cabinet so that the moisture therefrom may be evaporated by the circulation of air set up by the lowered temperature.

7. A refrigerator comprising a cabinet 25 with heat insulating sides, spaced covered trays adapted to receive a chemical refrigerant superimposing one another, drain pipes connecting said trays, fine wire screens protecting the entrances to said drain pipes, stop- 30 cocks in said drain pipes, said trays having openings therethrough forming communication with the interior of said cabinet.

8. A refrigerator comprising a cabinet with heat insulating sides, spaced curved 35 trays superimposing one another, said trays having flat tops and serving as horizontal partitions in the top, bottom and intermediate portions of said cabinet, said trays draining toward the centre and back, drain pipes 40 connecting said superimposed trays and disposed against the back wall of the cabinet, wire screens protecting the entrance to said drain pipes, stop-cocks controlling the flow therethrough, overlying covers providing access to said trays, the upper cover being perforated and spaced above the inner and solid cover whose cradle suspending means is perforated to permit circulation of air into the 45 interior of said trays, a solution of Chile salt-petre (NaNO_3), gravel and water, in said 50 ventilated trays and wet curtains hung in said cabinet so that the circulation of air set up by the lower temperature about said trays may cause evaporation of the moisture therefrom.

In testimony whereof I hereunto affix my signature.

ALBERT RIVARD.
